O E. Byrd.
Inventor

UNITED STATES PATENT OFFICE.

ORVAL E. BYRD, OF CRAWFORDSVILLE, INDIANA.

THILL-SUPPORT.

SPECIFICATION forming part of Letters Patent No. 452,634, dated May 19, 1891.

Application filed October 29, 1890. Serial No. 369,687. (No model.)

To all whom it may concern:

Be it known that I, ORVAL E. BYRD, a citizen of Crawfordsville, in the county of Montgomery and State of Indiana, have invented 5 certain new and useful Improvements in Attachments for Vehicles; and I do hereby declare the following to be a full, clear, and exact description of the invention, such as will enable others skilled in the art to which it applies to make and use the same.

My invention relates to an improvement in attachments for vehicles, the object being to produce a simple and efficient device for maintaining the shafts of the vehicle elevated when not in use, and by means of which rattling of the parts when in use will be prevented.

A further object is to produce a device for the purpose stated which shall be of simple 20 construction, easy of application to any vehicle, and one which shall be effective in the performance of its functions.

With these objects in view the invention consists in certain novel features of construction 25 and combinations and arrangements of parts, as hereinafter set forth, and pointed out in the claims.

In the accompanying drawings, Figure 1 is a side elevation of my improvement, showing 30 its application to the shaft of a vehicle for elevating the same. Fig. 2 is a similar view showing the portions of the parts when the device is employed to prevent rattling when the vehicle is in use. Fig. 3 is a plan view.

35 A represents the axle of a vehicle, to which a clip B is secured, the cross-bar a of said clip being extended and provided with an elongated slot b, for a purpose presently explained. The clip B also carries a thill-coupling C, to which the thill or shaft D is connected in any preferred manner.

Passing through the shaft D at a point somewhat removed from the coupling C is a bolt E, having an eye b' at its upper end for 40 the reception of one end of a spring F, said spring being provided with screw-threads at its end which passes through the eye b', and provided with nuts c at each side of said eye. From its connection with the shaft D the 45 spring F extends rearwardly and passes

through the elongated slot b in the cross-bar a of clip B, being provided with a bent portion or shoulder e, for a purpose which will be explained farther on. The spring F, after passing through the slot b, is formed into a 55 coil F', located under the axle, and its free end then bent forwardly and made in hook shape, as at F², and adapted to embrace the shaft D in proximity to the coupling C and bear on the top of said shaft, as shown most clearly in Fig. 3.

When the vehicle is not in use and it is desired to maintain the shafts elevated, said shafts will be elevated manually until the spring F has passed through the slot b in the 65 cross-bar a sufficiently to permit the shoulder e to engage the end of slot b of the cross-bar a, whereby the shafts will be maintained in an elevated position. When it is desired to use the vehicle and therefore to lower the 70 shafts or thills D, the spring F will be pressed inwardly until the shoulder e can pass through the slot b, whereupon the shafts or thills can be readily lowered. In this position the spring F will bear against the end wall of the 75 slot b with considerable force and the hooked end F² made to bear with considerable pressure upon the shaft in proximity to the coupling C. In this way the coupling C will be effectually prevented from rattling. 80

Slight changes might be made in the details of construction of my invention without departing from the spirit thereof or limiting its scope. Hence I do not wish to limit myself to the precise details of construction 85 herein described; but,

Having fully described my invention, what I claim as new, and desire to secure by Letters Patent, is—

1. The combination, with the shafts and 90 axle of a vehicle, of a spring adjustably secured to the shafts at one end, said spring being extended around the axle and at its other end provided with a hook-shaped portion to bear on the shafts, substantially as 95 set forth.

2. The combination, with the shafts and 100 axle of a vehicle, of a slotted bar secured to the axle, a spring having a spiral turn therein, said spring secured at one end to the shafts

and adapted to extend through said slotted bar and have a sliding movement therein, said spring being provided with a shoulder adapted to engage the end wall of the slot in the slotted bar and extend around the axle and bear on the shafts, substantially as set forth.

In testimony whereof I have signed this specification in the presence of two subscribing witnesses.

O. E. BYRD.
